(57) **CLAIM**

The ornamental design for a lock member as shown and
described.

DESCRIPTION

FIG. 1 is a front, top, right side perspective view of the lock
member showing the new design;

FIG. 2 is a right side elevational view thereof;

FIG. 3 is a top plan view thereof;

FIG. 4 is a left side elevational view thereof;

FIG. 5 is a bottom plan view thereof;

FIG. 6 is a front side elevational thereof; and,

FIG. 7 is a rear side elevational view thereof.

The ornamental design which is claimed is shown in solid
lines in the drawings.

The evenly spaced broken lines in the drawings illustrate
portions of the lock member and form no part of the claimed
design.

The uneven broken lines define the bounds of the claimed
design and form no part thereof.
